No. 37,288.

Patented January 3, 1905.

UNITED STATES PATENT OFFICE.

WILLIAM THOMPSON, OF KALAMAZOO, AND WILLIAM L. BERTRAM, OF DETROIT, MICHIGAN, ASSIGNORS TO THE KALAMAZOO STOVE COMPANY, OF KALAMAZOO, MICHIGAN.

DESIGN FOR A COOKING STOVE OR RANGE.

SPECIFICATION forming part of Design No. 37,288, dated January 3, 1905.

Application filed December 12, 1904. Serial No. 236,592. Term of patent 7 years.

To all whom it may concern:

Be it known that we, WILLIAM THOMPSON, residing in the city of Kalamazoo, county of Kalamazoo, and WILLIAM L. BERTRAM, residing in the city of Detroit, county of Wayne, State of Michigan, citizens of the United States, have invented a new, original, and ornamental Design for Cooking Stoves or Ranges.

Our new, original, and ornamental design for a cooking stove or range is clearly illustrated in the accompanying drawing, which is a perspective view thereof.

What we claim as new, and desire to secure by Design Letters Patent, is—

The ornamental design for a cooking stove or range, substantially as shown.

WILLIAM THOMPSON.
WILLIAM L. BERTRAM.
